UNITED STATES PATENT OFFICE.

HENRY D. AUPKE, OF SHARPSBURG, PENNSYLVANIA.

RAIL-JOINT.

SPECIFICATION forming part of Letters Patent No. 762,113, dated June 7, 1904.

Application filed March 16, 1904. Serial No. 198,498. (No model.)

To all whom it may concern:

Be it known that I, HENRY D. AUPKE, a citizen of the United States, residing at Sharpsburg, in the county of Allegheny and State of Pennsylvania, have invented new and useful Improvements in Rail-Joints, of which the following is a specification.

This invention relates to rail-joints, the object in view being to provide a splice or joint for the meeting ends of railway-rails whereby said ends may be firmly connected and braced without the aid of the usual bolts and nuts and the disadvantages incident thereto.

A further object of the invention is to provide a rail-joint consisting of a pair of fish-plates or splice-bars having formed integrally therewith means whereby the said plates or bars are adapted to interlock with each other and at the same time engage the rail ends.

With the above and other objects in view the invention consists in the novel construction, combination, and arrangement of parts, as hereinafter fully illustrated, described, and claimed.

In the accompanying drawings, Figure 1 is a perspective view of a rail-joint embodying the present invention. Fig. 2 is a detail perspective view of one of the fish-plates or splice-bars. Fig. 3 is a similar view of the other fish-plate or splice-bar, and Fig. 4 is a vertical cross-section through the joint.

Like reference-numerals designate corresponding parts in all the figures of the drawings.

Referring to the drawings by numerals of reference, 1 and 2 designate two contiguous rail ends, while 3 and 4 represent the fish-plates or splice-bars formed in accordance with the present invention, said splice-bars being adapted to be arranged at opposite sides of the rail ends and to extend across the joint therein or point where the rail ends meet or approach each other. The plates or bars 3 and 4 are in the main of the usual construction, each comprising the upright body portion 5 and the base portion or flange 6, which extends over the flange at one side of the rail. One of the splice-bars is provided with a series of studs or lugs 7, projecting inward from 50 the inner face thereof, as best illustrated in

Fig. 3, said studs being preferably formed as integral parts of the plate or bar and each stud being provided with V-shaped notches 8 at the top and bottom thereof, thereby providing a dovetailed head or extremity 9. All 55 of the dovetailed extremities or heads 9 are arranged in longitudinal alinement with each other. The other fish-plate is provided with a dovetailed groove 10, extending the entire length thereof and opening out at each end of 60 the plate. At points intermediate the ends of the groove 10 the overhanging walls at opposite sides of the groove are notched or cut away, as shown at 11, the notches 11 being arranged in oppositely-located pairs, as shown, 65 and of a size adapted to admit the dovetailed heads or extremities 9 of the studs 7.

The rail ends are provided with holes 12 to receive the studs 7, and the fish-plates or splice-bars are placed at opposite sides of the rail 70 ends, so that the studs 7 pass through the holes 12 and enter the notched entrances 11. After the parts are positioned in the manner just described one of the splice-bars or fish-plates is driven endwise until the studs are 75 moved out of alinement with the notches 11, thus carrying the shoulders of the dovetailed heads or extremities 9 behind the overhanging shoulders at opposite sides of the dovetailed groove 10. In this way the two fish- 80 plates or splice-bars are effectively interlocked and held snugly and closely against opposite sides of the rail ends.

The lower flanges 6 of the plates or bars 3 and 4 are notched, as shown at 13, to receive 85 securing-spikes 14, which are driven into the ties and which serve to prevent endwise movement between said plates, the spikes also assisting in crowding the fish-plates inward against the rail ends.

By means of the construction above described it will be seen that the employment of bolts and nuts is dispensed with and the disadvantages incident to the use of the same, the plates or bars being connected together and held against the rail ends by means formed integrally with or carried by said plates or bars.

Having thus described the invention, what is claimed as new is—

1. A rail-joint comprising a pair of fish-

100

plates, one of which is provided in its inner face with a dovetailed groove continuing fully in a longitudinal direction from end to end of the plate and opening out through opposite terminals of the latter, enlarged at intervals to form entrances, the other plate being provided with studs insertible through openings in the rail ends and provided with dovetailed heads or extremities receivable in the entrances to the dovetailed groove in the first-named plate, whereby the said plates are adapted to be interlocked by relative endwise movement, substantially as described.

2. A rail-joint comprising a pair of fish-
15 plates one of which is provided with a dove-
tailed groove continuing fully in a longitudi-
nal direction from end to end of the plate and
opening out through opposite terminals of the
20 latter, and the other provided with projecting
studs having dovetailed extremities, and means

for preventing relative endwise movement of
said plates.

3. A rail-joint comprising a pair of fish-
25 plates one of which is provided with a longi-
tudinal groove defined by undercut side walls,
and enlarged at intervals in its length to form
entrances, the other plate being provided with
studs having shouldered end portions insertible
30 through holes in the rail ends and receivable
in the entrances of the first-named plate, and
means for preventing relative endwise
movement of said plates after the studs have
been moved out of line with said entrances,
substantially as described.

In testimony whereof I affix my signature in 35
presence of two witnesses.

HENRY D. AUPKE.
